UNITED STATES PATENT OFFICE.

ALEXANDER MORTON AND MAURICE A. BRAAE, OF LABONTE, WYOMING.

WHEELED GRADER.

1,108,925.

Specification of Letters Patent.

Patented Sept. 1, 1914.

Application filed August 7, 1913. Serial No. 783,629.

To all whom it may concern:

Be it known that we, ALEXANDER MORTON and MAURICE A. BRAAE, citizens of the United States, residing at Labonte, in the county of Converse and State of Wyoming, have invented certain new and useful Improvements in Wheeled Graders, of which the following is a specification.

This invention relates broadly to agriculture implements, and has particular reference to new and useful improvements in graders of the scraper type.

As its principal object, the present invention contemplates the provision of a grader constructed in such manner that the scraping element proper may be lifted up and out of engagement with the ground by the manipulation of levers operable from the driver's seat.

An object of equal importance with the foregoing is to construct the scraping element and its associated lifting mechanism in such manner that at the will of the operator either the forward or rear terminal of the scraper may be lifted from engagement with the ground or road-bed, so that when the grader is employed in hilly countries, where the inclines and depressions are unusually severe, the terminals of the scraping element may be separately adjusted to prevent undue engagement with the ground.

A further object is to provide a wheeled grader constructed with such regard to proportion, number, and arrangement of parts that it may be cheaply manufactured, will be durable and efficient in its action, and is formed of a minimum number of parts, so that the liability of breakage or derangement, and consequent necessity of repair of the parts of the machine, will be reduced to a minimum.

The above and additional objects are accomplished by such means as are illustrated in the accompanying drawings, described in the following specification and then more particularly pointed out in the claims which are appended hereto and form a part of this application.

With reference to the drawings, wherein we have illustrated the preferred embodiment of our invention as it is reduced to practice, and throughout the several views of which similar reference numerals designate corresponding parts, Figure 1 is a perspective view taken from one rear corner of

the assembled structure and looking in the direction of the opposite forward corner; Fig. 2 is a side elevation with the scraper in elevated position; Fig. 3 is a vertical section taken longitudinally of the machine.

Proceeding now to the description of the drawings, the numeral 10 designates as an entirety the wheeled supporting frame in which the scraper is adjustably mounted. The wheeled supporting frame includes a Y-shaped body portion constructed preferably of two metallic bars 11 and 12, which are bent intermediate their length to produce the rearwardly diverging beams 13 and 14, and the stem beam 15, which as illustrated in the drawings includes the two terminals of the members 11 and 12 which are secured in the desired fixed relation to each other by means of a bolt or similar fastening device 16 and a removable king-pin 17. The king-pin 17 is formed integral with the bight portion of the U-shaped caster fork 18 at the lower terminal of which is carried a wheel 19. Obviously by thus providing a wheel of the pivoted caster type, the grader may be readily turned in a small compass. The supporting standard 20 of a spring seat 21 is arranged between the adjacent faces of the portion 15 and is held in position by the king-pin 17 and member 16.

The rear terminals of the beams 13 and 14 are secured adjacent the opposite ends of a squared axle 22 by means of U-shaped clamping bolts 23. In practice, the members 11 and 12 are bent so that the stem portion of the Y-frame will lie in a plane higher than that of the rear terminals, the obvious purpose of this construction being to facilitate the adjustment of the forward end of the moldboard frame or scraper when uneven ground is encountered. Wheels 24 and 25 of any desired type are provided with the axle 22.

The scraper, which is adjustably mounted in the wheeled frame above described, consists broadly in a substantially rectangular frame and a number of moldboards which are mounted transversely thereof and in parallel spaced relation to each other. The frame of the scraping element includes a pair of side beams 26 and 27, to the forward terminals of which are secured the lower terminals of a substantially U-shaped frame member 28. The frame member 28 is arranged with its bight portion upper-

most and is provided with a central aperture through which the king-pin 17 projects. Upon reference to Fig. 3 particularly, it will be observed that the bight portion of the member 28 is mounted for sliding movement on the king-pin 17 between the stem 15 of the Y-frame and the upper end of the fork 18.

The moldboards 29 are in the preferred embodiment formed of lengths of steel or cast iron, and are secured by bolts, rivets, or other suitable fastening devices 30 to the beams 26 and 27, being mounted, as above stated, in parallel spaced relation to each other and transversely to the line of draft of the grader. Hooks 31 are carried by the forward terminals of the members 26 and 27 and are provided for the attachment of swingletrees or double trees, as occasion may demand.

As a means for raising and lowering the moldboard frame, there has been provided three lifting levers 32, 33 and 34. The members 32 and 33 are respectively pivoted on segmental clutch plates 35 and 35' mounted at the rear terminals of the members 13 and 14. Wire cables or similar flexible elements 36 and 37 connect the levers 32 and 33 with the rear terminals of the side frame members 26 and 27. In securing the terminals of the flexible element to the members 26 and 27, the preferred embodiment of this invention employs metallic rings 38 which are disposed in apertures formed in the frame members. The cables 36 and 37 operate on pulleys 39 and 40 which are journaled in brackets 41 and 42 formed integral with and extending upwardly from the rear terminals of the base plates 43 and 44 on which the members 34 and 35 are formed. The levers 32 and 33 are equipped with the usual clutch rod and associated spring mechanism, so that the driver of the grader may by manipulation of the levers adjust the rear terminal of the moldboard frame to any desired elevation.

For the adjustment of the forward end of the moldboard frame, there has been provided the lever 34 which is pivoted on the clutch plate 45 similar in construction to the members 34 and 35 and equipped with a similar base plate 46, pulley 47, and bracket 48. It will be obvious upon reference to Fig. 3 particularly, that by adjusting the lever 34, the driver may raise or lower the forward end of the moldboard frame which is operatively connected to the lever by a wire cable or similar flexible element 49. A draft tongue 50 carries an attaching iron 51 which is pivotally connected to the wheeled frame by a pivot pin 52 which is passed through the eyelet 53 of a pair of spaced irons 54 and 55 formed integral with and extending upwardly from the forward terminal of the plate 56. The

plate 56 is mounted for swinging movement on the king-pin 17, and is interposed between the frame member 28 and the stem 15 of the Y-frame. A removable bracing rod 57 is provided to strengthen the draft tongue.

In reduction to practice, we have found that the form of our invention, illustrated in the drawings and referred to in the above description as the preferred embodiment, is the most efficient and practical; yet realizing that the conditions concurrent with the adoption of our device will necessarily vary, we desire to emphasize the fact that various minor changes in details of construction, proportion and arrangement of parts may be resorted to, when required, without sacrificing any of the advantages of our invention, as defined in the appended claims.

What we claim is:

1. A grading machine including a Y-shaped supporting frame having a pair of rear wheels and a single forward wheel, a fork for the forward wheel and a king pin rising therefrom, the king pin being connected to and fixed with respect to the forward end of the frame, a substantially rectangular scraper, flexible means suspending the scraper from the frame, and a U-shaped frame member carried by the forward end of the scraper, said U-shaped member having its bight portion mounted for vertical sliding movement on the king pin.

2. A grading machine including a Y-shaped supporting frame having a pair of rear wheels and a single forward wheel, a fork for the forward wheel and a king pin rising therefrom, a shoulder formed at the junction of the fork and the king pin, the king pin being connected to and fixed with respect to the forward end of the supporting frame, a substantially rectangular scraper, flexible means carried by the supporting frame and connected to the scraper for suspending the scraper from the frame, and a U-shaped member carried by the forward end of the frame, said U-shaped member having its bight portion apertured and mounted for vertical sliding movement on the king pin, said shoulder being adapted to limit the movement of the U-shaped member.

3. A grading machine including a Y-shaped supporting frame having a pair of rear wheels and a single forward wheel, a fork for the forward wheel and a king pin rising therefrom, the king pin being connected to and fixed with respect to the forward terminal of the frame, a shoulder formed at the junction of the fork and the king pin, a scraper, flexible means suspending the scraper from the frame, means controlling the last-mentioned means for adjusting the elevation of the scraper, and

means for holding the scraper against longitudinal movement with respect to the frame, said last-mentioned means including a U-shaped member rising vertically from the 5 scraper and having an opening in its bight portion, said opening receiving the king pin and being of less diameter than the said shoulder, whereby the downward movement of the forward end of the scraper is limited

by the engagement of the U-shaped member 10 with the shoulder.

In testimony whereof we affix our signatures in presence of two witnesses.

ALEXANDER MORTON.

MAURICE A. BRAAE.
